INVENTOR.
Harry A. Palmer,

Geo. P. Kimmel. ATTORNEY.

UNITED STATES PATENT OFFICE.

HARRY A. PALMER, OF DORCHESTER, MASSACHUSETTS, ASSIGNOR TO PALMER INVENTIONS, INC., OF BOSTON, MASSACHUSETTS, A CORPORATION OF MASSACHUSETTS.

OPERATING MEANS FOR IMPELLERS.

Application filed April 11, 1927. Serial No. 182,804.

This invention relates to a driving mechanism for shaft impellers and is designed primarily for use in connection with internal combustion engines, but it is to be understood that a driving mechanism in accordance with this invention can be used in connection with any type of engine for which it is found applicable, and the invention has for its object to provide a driving mechanism for converting a reciprocatory motion into a rotary motion and whereby continuous power is had by obtaining a low speed drive from a high speed piston displacement.

Further objects of the invention are to provide a driving mechanism for shaft impellers, in a manner as hereinafter set forth, and which is comparatively simple in its construction and arrangement, strong, durable, thoroughly efficient in its use, readily assembled, and comparatively inexpensive to set up.

With the foregoing and other objects in view the invention consists of the novel construction, combination and arrangement of parts as hereinafter more specifically described, and illustrated in the accompanying drawings wherein is shown an embodiment of the invention, but it is to be understood that changes, variations and modifications can be resorted to which fall within the scope of the claim hereunto appended.

In the drawings wherein like reference characters denote corresponding parts throughout the several views:

Figure 1 is a vertical sectional view of an internal combustion engine, showing the adaptation therewith of a shaft impeller driving mechanism in accordance with this invention.

Figure 2 is a sectional plan of an internal combustion motor showing the adaptation thereof of a shaft impeller driving mechanism in accordance with this invention.

Figure 3 is a fragmentary view in side elevation of a driving mechanism.

Figure 4 is a fragmentary view in section, of a driving mechanism showing the adaptation thereof with respect to the cylinder of an internal combustion engine.

Figure 5 is a fragmentary view in perspective of a portion of the driving mechanism.

Figure 6 is a perspective view of an impeller operating or actuating member.

The driving mechanism, as shown by way of example, is set up in connection with an internal combustion engine of a construction similar to that disclosed in my application Sr. No. 182806 Filed April 11, 1927, 60 and such engine includes a cylinder 1, a balanced piston 2 operating in the cylinder 1 and closed at each end, and a pair of shaft impellers 3 which are connected to a power transmitting shaft 4. Each impeller is in 65 the form of a wheel cam and provides means for driving the shaft 4. The driving mechanism in accordance with this invention is connected with the piston 2 and bodily carried thereby.

The driving mechanism in accordance with this invention includes a wrist pin 5 which extends through the piston 2, as well as the cylinder 1 and projects laterally a substantial distance from opposite sides of 75 the cylinder 1. The wrist pin 5 is bodily carried by the piston 2, during the reciprocations thereof, and the driving mechanism is so set up as to convert the reciprocatory motion of the piston into a rotating one for 80 the impellers 3 whereby the shaft 4 is carried with the impellers, as these latter are fixedly secured to said shaft as at 6. The cylinder 1 is formed with slots to provide for the travel of the wrist pin 5 during the 85 reciprocations of the piston. The cylinder 1 is formed on opposite sides with oppositely extending enlargements 7, 8 of channel shaped contour in sectional plan. The slots formed in the cylinder 1 for the passage of 90 the wrist pin 5 are indicated at 9. Secured in the enlargements 7 and 8 are vertically disposed guide members 10, 11 respectively and each of which is slotted as at 12 and said slots 12 register with the slots 9. The 95 inner faces of the guides 10, 11 at the sides thereof are offset as indicated at 13, 14 and with the offset portions 14 arranged outwardly with respect to the offset portions 13. The offset portions provide bearing surfaces 100 for roller bearings. The roller bearings are arranged in pairs and the roller bearings of each pair are indicated at 15, 16. The roller bearings 16 ride against the bearing surfaces formed by the offset portions 13 and the 105 roller bearings 15 ride against the bearing surfaces formed by the offset portions 14. The pairs of roller bearings are connected to the wrist pin 5 and carried thereby and during the travel of the wrist pin the said roller 110 bearings ride against the bearing surfaces

formed by the offset portions 13, 14. The wrist pin 5 is disposed at the transverse median of the piston 2 and the manner of setting up the bearing surfaces, which coact with the roller bearings, prevent any possibility of wabbling or displacement of the piston during its reciprocations and furthermore balances the piston during its movements.

- 10 The wrist pin 5 adjacent each pair of roller bearings is provided with an impeller operating member or element consisting of an annulus 17 mounted on bearings 18 and with the annulus of materially greater diameter than either one of the roller bearings of either pair. Each element 17 rides against the edge of an impeller 3 and is of the same width as the edge of the impeller.

Secured to the wrist pin 5, at each end 20 thereof, as well as depending therefrom is a holder element referred to generally by the reference character 19 and which includes a triangular shaped upper portion 20, which is fixedly secured to the end of the wrist pin, as at 21. The lower end of the portion 20 is provided with a stub shaft 22 extending inwardly therefrom and carrying a roller bearing 23 which rides against a ridge or cam surface 24 formed on the outer 30 face of the impeller 3. The holder element 19 further includes a fork shaped lower portion 25 which straddles hub 26 of the impeller and prevents twisting of the wrist pin during the reciprocation of the piston. 35 The roller 23 acts as a means to maintain the element 17 against the edge 27 of the impeller and the rolling of the element 17 against the edge 27 of the impeller 3 will provide for the rotation of such element 40 under such conditions carrying the shaft 4 therewith. The impellers 3 are of oval contour and in Figure 1 the high parts of the impellers are shown as engaged by the elements 17 and in Figure 2 the low parts 45 thereof. The cam surface or ridge 24 conforms substantially in contour to the edge 27 of the impeller. The impeller 3 forms no part of this invention and is not claimed, as the invention relates solely to the driving 50 mechanism for the impeller or rather im-

pellers, as the mechanism is constructed for driving two impellers in unison.

The construction and arrangement of the driving mechanism provides for the converting of reciprocatory motion into rotary motion and further provides whereby continuous power is had by obtaining a low speed drive from a high speed piston displacement. The pairs of rollers carried by the wrist pin 5 guide the same when it is bodily carried by the piston during the reciprocations of the latter, and as aforesaid the rollers coact with the bearing surfaces on the guides to prevent twisting or wabbling of the piston and further to maintain its balance. The setting up of the bearings in connection with the rolling parts of the mechanism reduces friction to a minimum and prevent overheating.

It is thought the many advantages of a driving mechanism for shaft impellers, in accordance with this invention, can be readily understood, and although the preferred embodiment of the invention is as illustrated and described, yet it is to be understood that changes in the details of construction can be had which will fall within the scope of the invention as claimed.

What I claim is:

In a shaft impeller driving mechanism for converting reciprocatory motion into rotary motion and with the impeller of the wheel cam type, a bodily shiftable wrist pin adapted to be connected transversely of and bodily carried with a reciprocating element, a pair of spaced impeller operating elements carried by said pin and each adapted to have rolling contact with an impeller for rotating it, a pair of holder elements each extended from one end of the pin and provided with a roller element having rolling contact with the impeller and providing means for maintaining an operating element in rolling contact with the impeller, said holder elements further including means to prevent twisting of said pin when bodily shifted by its reciprocating source.

In testimony whereof, I affix my signature hereto.

HARRY A. PALMER.
